UNITED STATES PATENT OFFICE.

DAVID ALLEN, OF NEW YORK, N. Y.

COIN-CHANGING MECHANISM.

Application filed December 6, 1921. Serial No. 520,304.

To all whom it may concern:

Be it known that I, DAVID ALLEN, a citizen of the United States, residing at New York, in the county of Bronx and State of New York, have invented certain new and useful Improvements in Coin-Changing Mechanism, of which the following is a specification.

This invention relates to change making mechanism for use on vending machines or otherwise.

The object of the invention is to provide a coin controlled mechanical device constructed so that the mechanism will actuate means for ejecting change for the full amount of the coin deposited, or the difference between the price of an article delivered and the value of the coin used to operate the delivery mechanism.

Another object is to provide a simple and efficient mechanism of this character including a container in which a plurality of cartons is stacked, each containing the requisite change, the lowermost of which is ejected with each rotation of the delivery drum and which is so protected as to prevent surreptitious removal of the cartons.

With these and other objects in view, the invention consists in certain novel features of construction as hereinafter shown, described and claimed.

In the accompanying drawings:—

Figure 1 represents a perspective view of a vending machine equipped with this improved change making device.

Fig. 2 is a longitudinal section through the vending mechanism with the upper portion broken off for convenience in illustration.

Fig. 3 is a horizontal section taken on the line 3—3 of Fig. 2.

Fig. 4 is a detail transverse section taken on the line 4—4 of Fig. 3.

Fig. 5 is a detail vertical sectional view of the carton containing portion of the device.

Fig. 6 is a perspective view of one end of the delivery drum showing the mechanism actuated thereby for ejecting a change carton, and,

Fig. 7 is a perspective view of one of the cartons, with parts broken out to show its contents.

In the embodiment illustrated, the change making apparatus is shown applied to a vending machine shown at 1 having mounted therein a rotary article discharge drum

2 which is equipped at one end with a lug 3, designed when the drum is turned for delivering an article purchased to engage one end of a link 4 positioned in the path of said lug and through said link actuate an ejecting lever 5. This lever 5 is fulcrumed on a suitable support and operates through a slot 6 in one wall of the casing of the vending machine, as is shown clearly in Fig. 4. 65

The casing 1 of the machine has an opening 7 in one side wall near its lower portion as is shown clearly in Fig. 1 and a tray 8 extends laterally outward from the bottom wall of said opening and is positioned directly below a container 9 which carries the cartons 10 containing the change.

The container 9 which is here shown secured to the casing 1 but which obviously may be located on any suitable support, 70 communicates at its lower end with the slot 6 through which the lever 5 operates, said lever being designed to move transversely across the lower end of said container for ejecting a carton 10 in a manner presently 80 to be described.

The link 4 which operates the lever 5 is shown mounted to slide longitudinally in suitable guides 4^a secured to the inner face of one of the side walls of the casing 1 as is shown clearly in Figs. 2 and 3. This link is provided at its opposite end with laterally extending lugs or fingers 11 and 12 arranged respectively one in the path of the drum carried lug 3 and the other loosely engaged 90 with the upstanding arm 5^a of the lever 5.

A coiled spring 13 is connected at one end with the upstanding arm 5^a of lever 5 and at its other end with a fixed member of the casing and exerts its tension to normally hold the lever in inoperative position as shown in Fig. 3 and to return it to such position after it has been actuated by the lug 3 on the dispensing drum, as will be presently more fully described.

The carton container 9 has an opening 14 extending throughout the greater portion of the length thereof and which is preferably covered with a transparent material so that it may be readily seen whether there are 105 any cartons 10 in the container.

A protective casing 15 is here shown enclosing the container 9 and extending down well over the lower end thereof having an opening in its front wall registering with the opening in the container and covered by a pane of glass 16 or other transparent

material so that the container 9 may be viewed therethrough. This casing 15 also has an opening 17 in the bottom thereof at one side of the container 9 for the discharge 5 therethrough of the carton 10 ejected by the lever 5.

A movable element here shown as a coin controlled dispensing drum 2 is rotated when a coin is dropped in the coin slot 18 10 of the machine and when rotated a distance sufficient to cause lug 3 to engage the lateral extension 11 of the link 4, said link will be moved longitudinally forward causing the ejecting lever 5 to swing on its 15 fulcrum and the arm thereof which is located adjacent the container 9 to swing through the slot 9^a in said container and eject the carton 10 which is resting on the bottom thereof. This carton will drop into 20 the tray 8 located below it and may be taken by the party desiring the change, the coin used to actuate the drum and for which change was desired drops into a receptacle suitably located to receive it.

25 As shown, the carton 10 contains four pennies which is designed to be the change between the cost of a cigar at six cents and the coin in the form of a dime which is used to actuate the drum. It is of course understood 30 that while this machine is shown for use in connection with a dime and an article valued at six cents, any other article may be delivered thereby and any other coin of any valuation desired may be used for operating it, the carton 10 containing the proper change, or the full value of the coin 35 when change only is desired.

After the drum 2 has been operated to discharge an article and is released, it will 40 be returned to normal position by any suitable means, not shown, and when so returned, the spring 13 will operate to return the lever 5 to normal position and to position the link 4 ready for actuation to 45 the next rotation of the drum 2.

It will thus be seen that this change making apparatus is extremely simple, the only part liable to become broken or inoperative.

being the coiled spring 13 which may be readily replaced, and that it may be applied 50 to many uses, for instance it may be used on telephone slot machines to make a full return or part; in subway change booths and many other places where change may be required or desired thereby dispensing 55 with the services of a cashier.

The preferred embodiment of the invention is disclosed in the drawings and set forth in the specification, but it will be understood that modifications within the scope 60 of the claimed invention may be made in the construction or use without departing from the principle of the invention or sacrificing any of its advantages.

I claim:

1. The combination of a movable member, a lever, a change container having separate packages of coins stacked therein and provided with a discharge opening, a coin ejector pivoted intermediately of the ends, 70 one end movable through said opening and a link connected with the other end of said lever and positioned in the path of said movable member whereby when said member is actuated in one direction, said lever 75 will be swung to eject a coin.

2. The combination of a movable member, a change container having cartons of coins stacked therein and provided at its lower end with a discharge opening, means for 80 protecting said opening against surreptitious removal of the cartons, a carton ejector in the form of a lever fulcrumed adjacent said container, and adapted to swing through the opening therein, said lever having 85 an upstanding arm, a link engaged with said arm and mounted in the path of said movable member whereby the movement of said member in one direction will actuate said lever to eject a carton, and a coiled 90 spring connected with said arm and with a fixed part of the machine for returning said lever to initial position after actuation.

In testimony whereof, I affix my signature hereto,

DAVID ALLEN.
